UNITED STATES PATENT OFFICE.

FREDERICK W. KRAUSE, OF CHICAGO, ILLINOIS.

SICKLE-GRINDER.

SPECIFICATION forming part of Letters Patent No. 227,366, dated May 11, 1880.

Application filed March 5, 1880. (Model.)

To all whom it may concern:

Be it known that I, FREDERICK W. KRAUSE, of Chicago, in the county of Cook and State of Illinois, have invented a new and useful Improvement in Sickle-Grinders, of which the following is a specification, reference being had to the accompanying drawings, illustrating the improvement, in which—

Figure 1 is an end elevation of my improvement attached to the end of the grindstone-frame, so that the grinding may be done on the periphery of the stone. Fig. 2 is a plan or top view of the improvement and a broken view of the grindstone and the frame to which it is hung. Fig. 3 is a vertical section through the socket-stand and clamping-bar on line Z, Fig. 2. Fig. 4 is an elevation of one of the thumb-cams for fastening the sickle to the clamping-bar. Fig. 5 is a view of the thumb-cam on line X, Fig. 4, looking down.

The principal features of the present invention consist in a ball-and-socket joint for giving the desired movement to the clamping-bar to which the sickle is attached, in combination with an adjusting-bar which is attached to the socket-plate of the ball-joint and has a partial revolution in a horizontal plane, whereby the sickle-clamp may be brought to or from the periphery of the stone, and by the same movement adjusted laterally with reference to the stone, by means of which the sickle may occupy any desired position on the stone for grinding suitable bevels.

A represent the two sides of an ordinary grindstone-frame, and B the ends thereof. C represents a socket-stand of ordinary construction, which in this instance is attached to the end rail, B, of the grindstone-frame.

D is a ball forming, with the part C, a ball-and-socket joint. This ball is provided with

a shank, E, which is rigidly affixed to a clamping-bar, F. The inside of this bar is provided with a groove, G, Figs. 1, 2, and 3, in which the bar of the sickle I is put, the sickle-blades projecting somewhat beyond the bar.

Thumb-cams J are put through ears K, formed on the bar F, so that by turning the cams the sickle is firmly fixed to the bar F.

The socket-stand C is combined with a slotted set-bar, L, which may be moved so as to adjust the socket-stand to any desired position. This construction is such that by means of the adjustment attained by the ball-and-socket joint and the set-bar L a greater range of bevels may be presented to the stone, and at the same time a great accuracy of grinding is attained.

The socket-stand C may be attached to the side of the grindstone-frame and answer the purpose well where sickles are to be ground on the flat side of the stone, the only change required being in the thumb-cams, which must be eccentric on their peripheries.

I claim and desire to secure by Letters Patent of the United States—

The ball-and-socket joint C D, for giving to the sickle-clamp F any desired position to bring the sickle to the periphery of the stone, so as to attain the requisite bevel to the knives, in combination with the adjusting-bar L, attached to the socket of the ball-joint, and adjustable to any desired position in a horizontal plane, and longitudinally adjustable to carry the sickle-clamp to or from the stone, as and for the purpose specified.

FREDERICK W. KRAUSE.
